United States Patent

Des. 239,359

Patented Mar. 30, 1976

239,359

COFFEE MAKER OR THE LIKE

Arthur J. Schmitt, West Bend, Wis., and William K. Fahey, Longwood, Fla., assignors to Dart Industries Inc., Los Angeles, Calif.

Filed June 20, 1974, Ser. No. 481,026

Term of patent 14 years

Int. Cl. D7—02

U.S. CL. D7—59

FIG. 1

FIG. 4-

FIG. 3-

FIG. 1 is a side elevational view of a coffee maker or the like, showing our new design;
 FIG. 2 is a top plan view thereof;
 FIG. 3 is a front elevational view thereof;
 FIG. 4 is a rear elevational view thereof; and
 FIG. 5 is a side elevational view thereof, taken from a side opposite that shown in FIG. 1.

We claim:

The ornamental design for a coffee maker or the like, substantially as shown and described.
